UNITED STATES PATENT OFFICE.

WILLIAM L. DODGE AND HUGH D. MACPHERSON, OF MAPLEWOOD, NEW JERSEY,
ASSIGNOR TO WESTERN ELECTRIC COMPANY, INCORPORATED, OF NEW YORK,
N. Y., A CORPORATION OF NEW YORK.

TELEPHONE SYSTEM.

1,387,367.

Specification of Letters Patent.

Patented Aug. 9, 1921.

Application filed August 7, 1919. Serial No. 315,816.

To all whom it may concern:

Be it known that we, WILLIAM L. DODGE and HUGH D. MACPHERSON, citizens of the United States, both residing at Maplewood, in the county of Essex and State of New Jersey, have invented certain new and useful Improvements in Telephone Systems, of which the following is a full, clear, concise, and exact description.

10 This invention relates to telephone systems and more particularly to such systems in which the signals for a plurality of trunk lines extending between widely separated stations are controlled over a single signaling path common to such trunk lines.

In systems of this character it has been proposed to employ at opposite ends of the signaling path, switching means for temporarily rendering the common signaling path individual to the various trunk lines served thereby. The individualizing switching apparatus may comprise means for translating into code signals the signals initiated by the different trunk lines, means for transmitting over the signaling path the code signals which are individual to the trunk lines, and means for receiving and translating the transmitted code signals into signals individual to the respective appropriate trunk lines.

30 In order that the common signaling path may be made to serve as many trunk lines as possible, it is desirable, in controlling the necessary signals between operators and subscribers in the building up and breaking down of connections over a trunk line, to transmit as few code signals as possible and to transmit the code signals as rapidly as possible. It is the object of the present 40 invention therefore to provide improved signaling means for systems of this character in which a minimum number of code signals for each connection established by way of a trunk line is transmitted, thereby rendering

the common signaling path available for 45 the transmission of code signals individual to other of the trunk lines to the end that the common signaling path may be made to serve a greater number of trunk lines.

In attaining this object of the invention 50 there is provided at the terminating station of the trunk lines and signaling path, apparatus individual to each trunk line which is responsive to the continued rapid opening and closing of the connected telephone line, 55 as when the subscriber at the station thereon is rapidly opening and closing the switch-hook contact to signal the originating operator, for setting up and transmitting over the common signaling path but two code signals during such continued rapid opening 60 and closing of the telephone line. Apparatus individual to each trunk line provided at the originating station is responsive to the two transmitted code signals causing the 65 operation of a signaling device associated with the engaged trunk line. This signaling device may preferably take the form of a signal lamp in a connected link circuit which is lighted intermittently during the continued opening and closing of the distant 70 connected telephone line to serve as a recall signal to the operator.

The invention may be more readily understood by a reference to the following 75 description considered in connection with the accompanying drawings, in which Figures 1 to 5 inclusive, when arranged in the manner indicated in Fig. 5, represent one embodiment of the invention. Referring 80 to Fig. 5 all apparatus shown to the left of the dotted line 2—2 is located at the office X, and that shown between the dotted lines 2—2 and 3—3 is located at the office Y, while that shown to the right of the dotted line 85 3—3 is located at the office Z. Like apparatus at the two offices X and Y will be designated by the same reference charac-

ters—without primes at the office X, and with primes at the office Y.

Referring to the drawings there is shown a toll trunk line L¹ comprising two talking conductors extending from a central office X to a central office Y. At central office X there is located a toll cord circuit F by means of which connection is established with the trunk line L¹. The 10 trunk line L¹ may be connected with a toll switching trunk circuit M extending from the central office Y to a central office Z, at which terminates a subscriber's telephone line N with which the toll switching trunk 15 circuit M may be connected. While only one toll cord circuit, one toll trunk line, one toll switching trunk, and one subscriber's telephone line are shown, it is to be understood that this is for the purpose of convenience only and that many such circuits and 20 lines may be and usually are provided, in actual service.

The signals for a plurality of toll trunk lines may be controlled over a signaling 25 path common to the trunk lines and comprising a conductor P, extending from a central office X to the central office Y, which conductor as shown has a grounded return. The signaling conductor is arranged in a 30 well-known manner for duplex operation, for which purpose there is provided at the ends of the conductor artificial balancing line AL and differential polarized relays 25 and 25'. Each end of the common signaling conductor 35 P is connected with a commutator for sending and receiving signals. These commutators are preferably of the well-known start-stop type of distributors employed in connection with printing telegraph systems and 40 are, it will be understood, provided with a synchronizing device (not shown) by means of which, approximate synchronism is automatically maintained therebetween.

The commutator at office X comprises a 45 sending distributor S for transmitting signals over conductor P to the office Y and a receiving distributor R for receiving signals transmitted over conductor P from the office Y, and similarly the commutator at the office 50 Y comprises a sending distributor S' and a receiving distributor R' for transmitting signals to and receiving signals from the office X over the conductor P. These commutators comprising sending and receiving 55 distributors are of the same construction and a description of one will be sufficient. For convenience, the construction of the sending and receiving distributors S and R only will be described, for the sending and 60 receiving distributors S' and R' are exactly like the former and need no specific description. The sending and receiving distributors

S and R each comprises a series of stationary rings some of which are continuous and others segmented and a common shaft upon 65 which are mounted brushes 9 and 10 normally held against rotation by the respective armatures of two separately controlled release magnets. The outer end of each brush is insulated from the inner end so that each 70 brush controls two separate groups of circuits. Between the common shaft and each brush there is provided friction clutch mechanism (not shown) by means of which the constantly rotating shaft causes the rotation 75 of each brush when released. The face of the sending distributor S is stationary and is provided with a common sending ring 14, a restoring segment r, a start segment s, and individual sending segments 1 to 6 for 80 controlling the signals transmitted over the signaling conductor P and with a common ring 15 and segments 16, 17 and 18 for controlling local circuits. The face of the receiving distributor R is also stationary and 85 is provided with a common receiving ring 19 and individual receiving segments 1 to 6 for selecting a circuit according to the case of signals received over the signaling conductor P, segments 20 and 21 through which 90 the selected signal receiving circuit is completed, segments 22 and 23 for controlling the circuit of the associated release magnet RRM and a ring 24 and segment 31 for controlling a local circuit. 95

At central office X the common conductor P is connected to the common sending segment 14, while the normal contact of the differential polarized relay 25 thereat is connected with the common receiving segment 19, and the alternate contact is connected with the segment 22 in such manner that when the relay 25 is operatively energized, the release magnet RRM is energized to release the brush 10. At the central office Y 105 the common conductor P is connected with the common sending segment 14', while the normal contact of the differential polarized relay 25' is connected with the common receiving segment 19', and the alternate contact of this relay is connected with the segment 22' in such manner that when the relay 25' is operatively energized, the release magnet R'RM is energized to release the brush 10'. 110

The signals transmitted over the common signaling conductor P by the sending distributors S and S' are determined by the polarity of current connected with the individual sending segments of the respective 120 sending distributors S and S'. These polarities are determined by the position of the brushes of automatic selector switches G and G' provided at the respective offices X and 115

Y. These automatic selector switches which are common to a plurality of trunk lines, are alike in structure. The automatic selector switch G is provided with eight brushes *a*, *b* and 1 to 6 mounted upon a single shaft driven by a motor magnet MM initially controlled by a start magnet 30 connected in the start conductor or lead ST common to the trunk lines. Brushes 1 to 6 are connected directly with the respective individual sending segments 1 to 6 of the sending distributor S. Brush *a* is connected with one winding of a relay 32 which controls the stopping of the motor magnet MM and the energization of the release magnet SRM of the sending distributor S. Brush *b* is connected with a contact of relay 32 for the purpose of assisting in the control of the switch as will more fully hereinafter appear. A slow releasing relay 33 and a release relay 34 associated with the automatic selector switch G are controlled by the sending distributor S for reasons which will more fully hereinafter appear. A plurality of contacts equal to twice the number of toll trunk lines to which the automatic selector switch G is common, is associated with each brush. The contacts associated with the different brushes are mounted at different levels in position to be engaged by the respective brushes as they are rotated by the motor magnet MM. Two correspondingly positioned contacts of all levels are allotted to each trunk line, for example, the first two contacts may be allotted to trunk line No. 1, the second two to trunk line No. 2, the third two to trunk line No. 3, etc. The two contacts of levels *a* and *b*, allotted to each trunk line, are connected with relays individual to and associated with the outgoing end of the trunk line. The trunk line represented in the drawings may be considered as trunk line No. 1. As shown, relays individual to the outgoing end of this trunk line No. 1 are connected by means of individual signal control leads A¹ and C¹ and restoring leads B¹ and D¹ with the allotted contacts of levels *a* and *b*, signal control leads A¹ and C¹ being connected to the respective first and second contacts of level *a* and restoring conductors or leads, B¹ and D¹ to the respective first and second contacts of level *b*. Each trunk line is provided with similar signal control and restoring leads at the office, similarly connected with the selector switch G. The automatic selector switches shown in the drawing are provided with sufficient contacts to accommodate thirty trunk lines. To the first and second contacts of the levels—one to six—allotted to the respective trunk lines, is connected current of the polarities in combinations as indicated in the following table, there being a different combination for each trunk line

and also for the first and second contacts allotted thereto.

The automatic selector switch G' located at the office Y is like the switch G in structure and is associated with the sending distributor S' in the same manner as switch G is associated with the sending distributor S. Similar start and motor magnets 30' and MM' and stopping, slow releasing and release relays 32', 33' and 34' are also provided for the automatic selector switch G'. This automatic selector switch G' is associated with the incoming ends of the trunk lines by means of three individual conductors and a common conductor. This switch G' is associated with the trunk line L¹, shown in the drawings, by means of the individual signal control leads A'¹ and C'¹ and restoring lead B'D'¹ and a common start lead ST', individual conductors or leads A'¹ and C'¹ being connected with the allotted first and second contacts of level *a'*, individual conductor of lead B'D'¹ with both allotted contacts of the level *b'* and the common conductor with the start magnet 30' of the switch G'. The selector switch G' is associated with each of the other trunk lines through similar signal control and restoring leads A', C' and B'D'. The polarities connected with the individual sending

100

105

110

115

120

125

segments 1' to 6' of the sending distributor S' are determined by the position of the brushes 1' to 6' of the switch G', and the different combinations of polarities connected with the allotted first and second contacts of the levels—one to six—for the various trunk lines are identical with those connected with the automatic selector switch G. These are shown in the preceding table.

10 In order that the signals transmitted from the office X by the sending distributor S and received at the office Y may be utilized, there are provided thereat six locking relays 41' to 46' inclusive, having energizing 15 windings connected with the respective individual receiving segments 1' to 6' of the receiving distributor R'. When a negative impulse is transmitted from a particular individual sending segment, the lock-up relay 20 connected with the corresponding individual receiving segment, will be energized and locked up. Lock-up relays 41' to 44' control a plurality of receiving and selecting relays 50' to 64' inclusive, which 25 coöperate with lock-up relay 45' to select a signal control circuit individual to a trunk line, while lock-up relay 46' controls the polarity of current connected with the selected signal control circuit. The individual 30 signal control circuits are connected with contacts of the relays 57' to 64' inclusive. Similar equipment is provided at the central office X for utilizing the signals transmitted from the office Y over the common 35 signaling conductor P.

Having in mind this brief description of the apparatus of the system shown in the drawings, it is thought that the invention will be more thoroughly understood from 40 a description of the operation of the system shown—

Connection of cord circuit F with trunk line L¹.

45 The operator at office X desiring to establish connection with the telephone line N which terminates at office Z, connection with which must be established through the office Y, communicates with the operator at 50 office Y over an order wire circuit (not shown). The operator at the office X ascertaining from the operator at office Y, that the connection with the telephone line N is to be completed by way of the trunk line 55 L¹, inserts calling plug 70 of cord circuit F into jack 71 of the trunk line L¹. Relay 73 thereupon operates over a circuit from battery through the winding of marginal relay 72, sleeve contacts of the plug 70 and 60 the jack 71 and the winding of relay 73 to ground. Relay 72 is marginal and does not operate at this time. Relay 73 in operating causes the energization of relays 74 and 75, relay 74 operating over a circuit from bat-

tery through the contact of relay 73, winding of relay 74 and the normal contact of relay 76 to ground, while relay 75 operates over a circuit from battery through the contact of relay 73, winding of relay 75 and the normal contact of relay 77 to ground. 70 Relay 74 in operating establishes a locking circuit for itself through one of its contacts to ground, and causes the energization of a differential relay 76 over a circuit from battery through the left-hand winding of relay 76 and an alternate contact of relay 74 to ground. Immediately upon energization, relay 76 by the closure of its inner left-hand alternate contact is rendered independent of relay 74, while relay 74 is locked 75 up independent of relay 76. Relay 74 in operating causes the energization of the start magnet 30 over a circuit from battery through the start magnet 30, common start lead ST, middle normal contact of relay 78, 80 right-hand contact of relay 79 and right-hand alternate contact of relay 74 to ground. Start magnet 30 closes the circuit of the motor magnet MM which is of the self-interrupting type. The motor magnet 85 advances all brushes of the selector G step-by-step until the brush *a* engages the contact to which the signal control lead A¹ is connected. This signal control lead A¹ was previously grounded by the energization 90 of relay 74 so that upon the engagement of the brush *a* with the first contact assigned to trunk line L¹, relay 32 operates over a circuit from battery through the upper winding of relay 32, brush *a*, signal 95 control lead A¹, left-hand normal contacts of relays 78 and 79, and an alternate contact of relay 74 to ground. Relay 32 in operating opens the operating circuit of motor magnet MM thereby stopping the advancement 100 of the brushes of the selector G. The relay 32 also completes a locking circuit for itself which may be traced from battery through the contact of relay 34, the middle alternate contacts and the lower winding 105 of relay 32 to ground. The operation of relay 32 causes the energization of relay 78 over a circuit from battery through the contacts of release relay 34 and slow releasing relay 33, upper alternate contact of relay 32, 110 brush *b*, restoring lead B¹, right-hand normal contact of relay 78, winding of relay 78, right-hand contact of relay 79 and an alternate contact of relay 74 to ground. Relay 78 in operating completes a locking circuit for itself from battery through its right-hand alternate contact and winding, right-hand contact of relay 79, and an alternate contact of relay 74 to ground. Relay 78 in operating removes the ground 115 from signal control lead A¹ connected thereto by the operation of relay 74, thereby 120 opening the energizing circuit of relay 32.

which, however, remains operated due to the closure of its locking circuit. Relay 32 in closing its lower alternate contact, causes the energization of the release magnet SRM 5 over a circuit from battery through ring 15, brush 9, and segment 16 of the sending distributor S, the lower alternate contact of relay 32, and the winding of release magnet SRM to ground. The attraction of the 10 armature of the release magnet SRM upon the energization thereof releases the brush 9 which is thereupon rotated through a complete cycle at the end of which the brush is stopped in its normal position. The 15 brush 9 in being rotated first engages start segment s thereby connecting positive current with the common signaling conductor P. This brush then moves out of engagement with the segment 16 thereby opening 20 the energizing circuit of and causing the deenergization of the release magnet SRM restoring its armature to normal position preparatory to stopping the brush when it reaches its normal position. From an in- 25 spection of the table of polarities, it will be observed that at the stopping of the automatic selecting switch G with the brushes thereof in engagement with the first of the two contacts allotted to trunk line L¹, positive current is connected with such first contacts on the first, second, fourth, fifth and sixth levels, while negative current is connected with such first contact of the third level. When the brush 9 engages segment 30 17, slow releasing relay 33 operates over a circuit from battery through segment 15, brush 9, segment 17 and the winding of relay 33 to ground. The operation of relay 33 removes battery from the brush b. As 35 the brush 9 successively engages the individual sending segments 1 to 6, currents of the polarity connected with these segments are successively connected with the conductor P. When brush 9 moves out of engagement 40 with segment 17 the energizing circuit of the slow-releasing relay 33 is opened and upon the engagement of brush 9 with segment 18 release relay 34 is energized over a circuit from battery through segment 15, 45 brush 9, segment 18 and the winding of the release relay 34 to ground. The energization of release relay 34 opens the locking circuit of relay 32, whereupon this relay releases. Relay 33 is made slow in releasing 50 so that its contact remains open until after the opening of the contact of release relay 34. As the brush 9 moves out of engagement with segment 18 release relay 34 is de- 55 energized. When brush 9 engages restoring 60 segment r, negative current is connected with the common signaling conductor P. The automatic selecting switch G is now in condition to be seized by another trunk line, since the trunk line L¹ is disconnected there-

from and the sending distributor S is in 65 normal condition.

The connection of positive current from segment s with conductor P causes the operation of the differential polarized relay 25' at office Y over a circuit from positive 70 battery through segment S, brush 9, common sending ring 14 and the junction point between the windings of differential polarized relay 25, then by one path through the lower winding of relay 25 and artificial line 75 to ground and by another path through the upper winding of relay 25, conductor P, both windings of the differential polarized relay 25', and the artificial line to ground. The operation of relay 25' causes the energization of release magnet R'RM over a circuit from battery through the alternate contact of relay 25', segment 22', brush 10', 80 segment 23' and the winding of release magnet R'RM to ground. The attraction of the 85 armature of the release magnet R'RM upon the energization thereof, releases the brush 10' which is thereupon rotated through a complete cycle at the end of which the brush is stopped in its normal position. As the 90 brush 10' moves out of engagement with the segments 22' and 23', the release magnet R'RM is deenergized and permits the restoration of its armature to normal position preparatory to stopping the brush when it reaches its normal position. When the brush 10' moves out of engagement with segment 31', relay 82' is deenergized, closing 95 its contact which is common to the locking circuits of relays 41' to 46' inclusive. The 100 armature of the differential polarized relay 25' remains in its alternate position as long as positive current is connected with the other end of conductor P and moves to its normal position whenever negative current 105 is connected with the other end of conductor P. The brushes 10' and 9 are being rotated at the same time and while brush 9 is in engagement with segment 3 to which negative current is connected, the armature of relay 110 25' moves to its normal position and brush 10' engages individual receiving segment 3'. Relay 43' thereupon operates over a circuit from battery through the normal contact of relay 25', common receiving ring 19', 115 brush 10', individual receiving segment 3' and the lower winding of relay 43' to ground. Relay 43' then locks up through its upper winding and contact and the contact of relay 82', and causes the operation of relays 51' and 52' over a circuit from battery, through windings of relays 52' and 51' and the lower contact of relay 43' to ground. 120 When the brush 10' engages segments 20' and 21', signal receiving relay 85 operates 125 over a circuit from negative battery 86' through the normal contact of relay 46', segment 20', brush 10', segment 21', normal con-

tact of relay 45', lower normal contact of relay 50', lower alternate contact of relay 51', upper normal contacts of relays 53' and 58', selected signal receiving conductor E¹, 5 individual to trunk line L¹, and the left-hand winding of relay 85 to ground. Relay 93 is energized in parallel with relay 85 but does not lock up, on account of the open contact of relay 92 which is not energized until 10 after the locking up of relay 85 and the release of relay 93. The energization of relay 93 at this time performs no useful function. Relay 85, in operating, completes a locking circuit for itself from battery through its 15 right-hand alternate contact and right-hand winding to ground. The operation of the relay 85, individual to the incoming end of the trunk line L¹, causes the lamp 90 to be lighted over a circuit from battery through 20 the right-hand alternate contact of relay 85, lower normal contact of relay 91 and the lamp 90 to ground. Relay 85 in closing its left-hand alternate contact connects supervisory relay 94 in circuit with the talking 25 conductors of the trunk line L¹ extending toward the plug. When the brush 10' moves out of engagement with the segments 20' and 21', the energizing circuit of relays 85 and 93 is opened causing the deenergization of 30 relay 93. Slow-releasing relay 92 is then energized over a circuit from battery through the right-hand alternate contact of relay 85, right-hand normal contact of relay 93 and the winding of relay 92 to ground. When 35 the brush 10' engages the segments 22' and 23', the armature of relay 25' is in its normal position, since brush 9 is connected with restoring segment r and negative current is connected with the conductor P, and the 40 energizing circuit of the release magnet R'RM will be open. The engagement of the brush 10' with the segment 31' causes the energization of relay 82' over a circuit from battery through the ring 24', brush 10', segment 31' and the winding of relay 82' to ground. The energization of relay 82' opens 45 the locking circuit of relay 43' which releases, causing the deenergization of relays 51' and 52'. All apparatus associated with 50 the automatic selecting switch G, the sending distributor S, the receiving distributor R and the relay selecting and receiving circuit, is now in normal condition, so that it may be associated with any other trunk line. 55 The lighting of the lamp 90 serves as a guard signal to the operator at the office Y, indicating that the operator at the office X has connected the toll cord circuit F with the proper trunk line L¹.

60 *Connection of toll switching trunk circuit M, with telephone line N.*

At the time the operator at the office Y, designated the trunk line with which the

operator of office X should connect the cord 65 circuit F, the operator at the office Y also communicated with the operator at the office Z over an order wire circuit (not shown) advising the operator at the office Z, the 70 number of the desired line whereupon the operator at the office Z designates the toll switching trunk circuit over which connection should be established. Assuming toll switching trunk circuit M to be that designated, the operator at the office Z, after designating this trunk, inserts plug 100 of the toll switching trunk circuit M into jack 101 of the telephone line N. Relay 102 and cut-off relay 103 thereupon operate over a circuit from battery through the winding of 75 relay 102, sleeve contacts of the plug 100 and the jack 101 and the winding of cut-off relay 103 to ground. The energization of relay 102 causes supervisory lamp 104 to be lighted over a circuit from battery through 80 the lamp 104, lower alternate contact of relay 102, resistance 105 and the normal contact of relay 106 to ground. The operation of cut-off relay 103 disconnects line relay 107 from the line wires of the telephone line N. 90

Connection of trunk line L¹ with toll switching trunk circuit M.

The operator at office Y observing the lighted condition of the lamp 90 inserts plug 95 110 of the trunk line L¹ into jack 111 of the toll switching trunk circuit M. Relay 112 thereupon operates over a circuit from battery through the winding of relay 112, sleeve contact of the plug 110 and the jack 101 and resistance 113 to ground. Relay 91 100 operates upon the energization of relay 112 and in opening its lower normal contact extinguishes the lamp 90. The energization of relay 91 also causes the operation of 105 supervisory relay 94 of the trunk line L¹ and relay 106 of the toll switching trunk circuit M over a circuit from battery through the left-hand winding of relay 106, left-hand normal contact of relay 108, tip 110 contacts of the jack 111 and the plug 110, upper alternate contact of relay 91, upper 115 normal contact of ringing relay 114, winding of supervisory relay 94, left-hand alternate contact of relay 85, lower normal contact of ringing relay 114, ring contacts of the plug 110 and the jack 111, the right-hand normal contact of relay 108 and the right-hand winding of relay 106 to ground. The energization of relay 106 opens the circuit of and extinguishes the lamp 104.

The energization of the supervisory relay 94 causes the energization of relays 116, 117, 118 and 119, the energizing circuit for relay 116 being from battery through the winding 125 of relay 116 and the alternate contact of supervisory relay 94 to ground. The energizing circuit for relays 117 and 118 may be

traced from battery through the winding of relay 117, the left-hand contact of relay 120, winding and normal contact of relay 118, left-hand normal contact of relay 119, right-hand contact of relay 120, right-hand normal contact of relay 121 and the alternate contact of supervisory relay 94 to ground. Relays 117 and 118 upon being energized are locked up over a circuit from battery 5 through the winding of relay 117, left-hand contact of relay 120, winding and middle alternate contact of relay 118 to ground. The energizing circuit for relay 119 may be traced from battery through the winding of relay 119, right-hand normal contact thereof, right-hand contact of relay 120, right-hand normal contact of relay 121 and the alternate contact of supervisory relay 94 to ground. Relay 119 upon being 10 energized opens its left-hand normal contact which is in the energizing circuit of relays 117 and 118, and completes a locking circuit for itself from battery through the winding and alternate contact of relay 119, left-hand 15 normal contact of relay 122, right-hand normal contact of relay 121 and the alternate contact of supervisory relay 94 to ground. The energizing circuits for relays 116, 117, 118 and 119 are closed simultaneously and 20 the energization of relay 119 as already explained opens a contact in the energizing circuit of relays 117 and 118. In order that this contact may not be opened until after relays 117 and 118 have been energized relay 25 119 is made slightly slower in operating than relays 117 and 118, but is sufficiently fast in energizing and deenergizing that it follows the energization and deenergization of the supervisory relay 94. The energization of 30 relay 118 causes the operation of relay 123 over a circuit from battery through the right-hand alternate contact of relay 85, winding of relay 123, left-hand normal contact of relay 124 and the right-hand alternate contact of relay 118 to ground. Relay 45 123 in closing its contact prepares an energizing circuit for relay 124, which, however, as long as relay 118 is energized, is short-circuited by the left-hand normal contact of 50 relay 124 and the right-hand alternate contact of relay 118. Relay 118 in closing its left-hand alternate contact grounds the signal control conductor A'^1 connected with the first of the two contacts on level a of automatic selecting switch G' allotted to trunk line L^1 . The energization of relay 117 causes the energization of the start magnet 30', which thereupon closes the operating circuit to the motor magnet MM' . This motor magnet which is of the self-interrupting type thereupon advances the brushes of the switch G' step-by-step until the brush a' engages the contact to which the signal control conductor A'^1 is connected when relay 55 32' is energized to open the circuit of motor magnet MM' . The relay 32' upon being energized completes a locking circuit through its left-hand winding and in closing its right-hand alternate contact causes the energization of relay 120 over a circuit from battery through the contacts of release relay 34' and slow releasing relay 33', right-hand alternate contact of relay 32', brush b' , restoring conductor $B'D^1$ and the winding of relay 120 to ground. Relay 120 upon being 60 energized opens the locking circuits of relays 117 and 118. The resulting deenergization of relay 117 opens the energizing circuit of start magnet 30'. The opening of the left-hand alternate contact of relay 118 removes the ground connection from the signal control conductor A'^1 . The opening of the right-hand alternate contact of relay 118 upon the deenergization thereof removes the short-circuit about the winding of relay 124, which thereupon operates over a circuit from battery through the right-hand alternate contact of relay 85, winding and contact of relay 123, winding of relay 124 and the left-hand normal contact of relay 121 to 65 ground. The closure of the left-hand alternate contact of relay 32' causes the energization of the release magnet $S'RM$ of the sending distributor S' over a circuit from battery through ring 15', brush 9', segment 16', left-hand alternate contact of relay 32' and the winding of the release magnet $S'RM$ to ground. 70

The sending distributor thereupon functions to successively connect with the common signaling conductor P currents of the polarities connected with the individual sending segments of this distributor. The polarities connected with the sending segments 1' to 6' are determined by the polarities connected with the contacts engaged by the brushes 1' to 6'. To restoring segment r' negative current is permanently connected while positive current is permanently connected with start segment s' . Since trunk line L^1 is the trunk line now involved, positive current is connected with segments 1', 2', 4', 5' and 6', while negative current is connected with segment 3'. While the brush 75 9' is making a complete cycle, the release magnet $S'RM$ is deenergized when the brush moves out of engagement with segment 16', the circuit of the slow-releasing relay 33' is closed during the time the brush is in engagement with segment 17', and the release relay 34' is energized during the time the brush is in engagement with the segment 18', whereby the apparatus associated with the sending distributor S' and the automatic selecting switch G' functions in the same 80 manner as that associated with the sending distributor S and the automatic selecting switch G . Relay 120 becomes deenergized 85

90

95

100

110

115

120

125

upon the energization of the slow releasing relay 33'. Relays 117 and 118 are not energized upon the release of relay 120, for the energizing circuit of these relays 117 and 118 5 is open at the left-hand normal contact of relay 119 which is locked up at this time.

The differential polarized relay 25 connected in the common signaling conductor P at the office X operates when the brush 9' 10 engages the individual sending segment S', whereupon the release magnet RRM of the receiving distributor R is energized to release the brush 10. When the brush 9' later engages the sending segment 3', the relay 25 15 is deenergized whereupon relay 43 energizes over a circuit from battery through the normal contact of relay 25, common receiving segment 19, brush 10, individual receiving segment 3 and the lower winding of relay 43 20 to ground. Relay 43 thereupon locks up through its upper winding and contact and the contact of the now deenergized relay 82. Relays 51 and 52 operate upon the energization 25 of relay 43. Later upon the engagement of the brush 10 with the segments 20 and 21, relay 77 operates over a circuit from negative battery 86 through the normal contact of relay 46, segment 20, brush 10, segment 21, lower normal contacts of relays 45 30 and 50, lower alternate contact of relay 51, upper normal contacts of relays 53 and 58, signal receiving conductor E¹ and the left-hand winding of signal receiving relay 77 to ground. Relay 77 thereupon locks up 35 through its right-hand windings and right-hand alternate contact, opening the energizing circuit of the slow releasing relay 75, and grounds resistance 130, thereby connecting this resistance in parallel with the winding 40 of relay 73. The resistance of the circuit including the winding of the marginal relay 72 is thereby reduced to such an extent that the relay 72 operates to light the supervisory lamp 131. When brush 10 of the receiving distributor R reaches its normal position 45 relay 82 is operated whereupon relays 43, 51 and 52 are restored to their normal condition. The lighting of the supervisory lamp 131 serves as a signal to the operator 50 at the office X that the connection has been completed through to the line of the wanted subscriber and that the established circuit is in condition for signaling the subscriber of the wanted line.

55 *Operator at office X, actuates ringing key.*

The operator at office X upon observing the lighted condition of the supervisory lamp 131 may actuate ringing key 132 which 60 connects a source of ringing current 133 with the talking conductors of the cord circuit F and the trunk line L¹. Relay 134 is thereupon operated causing the energization of relay 79. The energization of relay 79

opens the locking circuit of and causes the 65 release of relay 78.

Operator at office X restores ringing key.

Upon the restoration of the ringing key 132 to normal position relay 134 releases, 70 causing the deenergization of relay 79, thereby closing its left-hand contact to ground the signal control conductor A¹. The deenergization of relay 78 followed by the deenergization of relay 79 reestablishes 75 the energizing circuit for the start magnet 30, whereupon the automatic selector switch G and the sending distributor S function in the same manner as when the plug 70 was inserted into the jack 71 transmitting the 80 same combination of impulses over the common signaling conductor P. The receiving distributor R' also functions as before to receive and distribute the combination of impulses whereby the relay 82' is released, 85 relay 43' energized and locked up and relays 51' and 52' operated. Then when the brush 10' engages the segments 20' and 21', relay 93 operates due to an impulse over a circuit from negative battery 86', through 90 the lower normal contact of relay 46', segment 20', brush 10' and segment 21' of the receiving distributor R', lower normal contacts of relays 45' and 50', lower alternate 95 contact of relay 51'; upper normal contacts of relays 53' and 58', signal receiving conductor E'¹ and the right-hand winding of signal receiving relay 93 to ground. Relay 93 immediately locks up over a circuit from battery through its left-hand winding 100 and left-hand alternate contact and the contact of relay 92 to ground. The opening of the right-hand normal contact of relay 93 opens the energizing circuit of the slow release relay 92, while the closure of the right-hand alternate contact of relay 93 causes the energization of the slow release relay 135 over a circuit from battery through the right-hand alternate contacts of relays 85 105 and 93 and the winding of relay 135 to 110 ground. Relay 135 in operating causes the operation of a slow release relay 136 and ringing relay 114, these relays operating in parallel upon the closure of the right-hand contact of relay 135. The opening of 115 the normal contacts of ringing relay 114 causes the deenergization of supervisory relay 94, but relays 116, 119, 123 and 124 do not release for they are held operated through the contact of relay 136 which is 120 energized while the ringing relay 114 is energized. The opening of the contact of relay 92 upon the full release thereof opens the locking circuit of relay 93 which thereupon releases. The opening of the right-hand alternate contact of relay 93 causes the release of the slow releasing relay 135 which in opening its right-hand contact opens the 125

tact of relay 32', brush 3', restoring conductor B'D' and the winding of relay 120 to ground. Relays 117 and 121 are deenergized upon the energization of relay 120.

5 The brushes of the selector switch G' engaging the second set of contacts allotted to the trunk line L¹ connects a current of positive polarity with the individual sending segments 1', 2', 4' and 5', and current 10 of negative polarity to the individual sending segments 3' and 6'. The energization of relay 32' causes the energization of the release magnet S'RM associated with the sending distributor S', whereby the brush 9' 15 is released and makes a complete revolution to transmit over the common signaling conductor P a combination of impulses determined by the polarities connected with the contacts of the automatic selector switch G' 20 engaged by the brushes 1' to 6'. When the combination of impulses has been transmitted, the sending distributor S' and the automatic selector switch G' and associated apparatus are restored to normal position, 25 and the relay 120 is deenergized. These transmitted impulses being received at the office X, cause the energization and locking up of relays 43 and 46 as the brush 10 of the receiving distributor R passes over the individual receiving segments 3 and 6 thereof. 30 The operation of relay 43 causes the energization of relays 51 and 52 in the manner hereinbefore described. Since relay 46 is energized when brush 10 engages the segments 20 and 21 of the receiving distributor R, the signal receiving relay 77 will be differentialized and released. This is brought about by connecting a positive impulse from battery 99 with the original energizing circuit of relay 77. The relation of the number of turns of the two windings of signal receiving relay 77 is such that when positive current traverses the left-hand or energizing winding of this relay at the same time that 35 negative current is traversing the right-hand or locking winding the relay is differentialized and releases its armatures. The opening of the left-hand alternate contact of this relay disconnects the resistance 130 from 40 parallel relation with the winding of relay 73, whereupon the marginal relay 72 releases its armature and extinguishes the lamp 131. Relay 77 in releasing also causes the operation of the slow-release relay 75, restoring 45 the apparatus at the office X to the same condition as it was prior to the insertion of the plug 110 into the jack 111. The extinguishment of the lamp 131 serves as a signal to the operator at the office X that the wanted subscriber has responded.

Subscriber restores receiver to switchhook.

At the conclusion of the conversation the subscriber at the station on telephone line 65 N restores the receiver to the switchhook

thereby releasing supervisory relay 145 which opens a circuit of and releases relay 108. Relay 106 is thereupon connected in circuit with supervisory relay 94 thereby causing the energization of this relay 94. 70 Just prior to the energization of the supervisory relay 94, all relays individual to the incoming end of the trunk line L¹ which are controlled by the supervisory relay 94 are deenergized.

75 The energization of the supervisory relay 94 causes the operation of relays 116, 117, 118 and 119 in the manner before described, causing the movement of the automatic selector switch G' until its brush a' engages 80 the grounded signal control conductor A', when the sending distributor S' transmits over the conductor P, the same combination of impulses transmitted when the plug 110 was inserted in the jack 111. The operation of relay 118 also causes the energization of relay 123. Relay 120 also operates when relay 32' is energized to release relays 117 and 118. Upon the release of relay 118, relay 124 operates. Upon the return of the 85 brush of the sending distributor S' to normal position and the release of relays 117 and 118, the automatic selector switch G' and the sending distributor S' are freed from the trunk line L¹ and may thereafter be temporarily associated with any other trunk line. The transmitted combination of impulses is received at the office X through the action of the relay 25 and the receiving distributor R causing through the energization of relays 43, 51 and 52 the energization and locking up of signal receiving relay 77 90 in the manner previously described. Resistance 130 is thereupon connected in parallel with the winding of relay 73 to cause the operation of relay 72, whereby the supervisory lamp 131 is lighted to furnish a disconnect signal. Relay 75 releases upon the energization of relay 77. Following the energization of relay 77, the brush 10 is stopped in its normal position and relay 82 is energized causing the deenergization 95 of relays 43, 51 and 52.

Operator at office X disconnects toll cord circuit F from trunk line L¹.

100 The operator at office X upon observing the lighted condition of the supervisory lamp 131 withdraws the plug 70 from the jack 71, causing the release of relays 72, 73, 74 and 78. The release of relay 72 opens the circuit of and extinguishes the supervisory lamp 131. The release of relay 74 causes the energization of start magnet 30 over a circuit from battery through the winding of start magnet 30, start lead ST, outer right-hand alternate contact of relay 76 and the right-hand normal contact of relay 74 to ground. The deenergization of relay 74 105 also grounds conductor C¹ connected with 110

energizing circuit of ringing relay 114 and slow releasing relay 136. Ringing relay 114 releases before relay 136 and upon the closure of the normal contact of this ringing relay 114, supervisory relay 94 is immediately energized. The contact of relay 136 is not opened until after the closure of the alternate contact of the supervisory relay 94.

While ringing relay 114 is energized the source of ringing current 137 is connected with the toll switching trunk circuit M to cause the energization of ringing response relay 138. While the energizing circuit of relay 106 is opened by the opening of the normal contacts of ringing relay 114, relay 106 does not have time to close its normal contact before the closure of the upper alternate contact of the ringing relay 114, when a temporary holding circuit for relay 106 is completed from battery through the left-hand winding of relay 106, left-hand normal contact of relay 108, tip contacts of the jack 111 and the plug 110, upper alternate contact of relay 91 and the upper alternate contact of ringing relay 114 to ground. The response of relay 138 causes the operation of relay 108 and ringing relay 139 over a circuit including the left-hand winding of relay 108 and the winding of ringing relay 139 in series and the contact of relay 138. The energization of relay 108 closes its alternate before opening its normal contacts, thereby establishing a substitute holding circuit through the left-hand winding of relay 106. Therefore, the lamp 104 is not lighted during the energization of the ringing relay 114. Upon energization, ringing relay 139 connects the source of ringing current 140 with the line of subscriber N for causing the operation of the usual call bell 141 at the station. Upon the release of relay 114 ringing current from the source 137 is disconnected from the toll switching trunk circuit M and ringing response relay 138 releases, causing the deenergization of relay 108 and ringing relay 139. The release of relay 108 connects both windings of relay 106 in circuit with the supervisory relay 94 before the holding circuit of relay 106 is opened at the alternate contact of relay 108, whereby this relay 106 remains energized. The deenergization of relay 139 disconnects ringing current from the source of current 140 from the line of subscriber N.

Subscriber of telephone line N, removes receiver from switchhook.

The subscriber at the station on telephone line N, in responding to the operation of the call bell 141, removes the receiver from the switchhook, thereby causing the operation of supervisory relay 145 over a circuit from battery through the winding of supervisory relay 145, upper normal contact of ringing

relay 139, ring contacts of the plug 100 and the jack 101, out over one side of the line, through the substation apparatus and back over the other side of the line, tip contacts of the jack 101 and the plug 100, upper alternate contact of relay 102 and lower normal contact of ringing relay 139 to ground. Supervisory relay 145 in operating causes the energization of relay 108 over a circuit from battery through the left-hand winding of relay 108, contact of supervisory relay 145, right-hand winding of relay 108 and the alternate contact of relay 106 to ground. Relay 108 in operating closes its alternate and opens its normal contacts, whereby relay 106 is disconnected from the circuit including the supervisory relay 94, and is maintained energized through its left-hand winding and the alternate contact of relay 108. Relay 108 in operating also causes the deenergization of the supervisory relay 94. The supervisory relay 94 in opening its alternate contact, opens the energizing circuit of slow releasing relay 116 and the holding circuit of relay 119. Relay 116 is slow in releasing so that before it releases its armature relay 146, which is slow to release, is operated over a circuit from battery through the winding of relay 146, alternate contact of relay 116 and the normal contact of supervisory relay 94. This relay 146, however, performs no useful function at this time. Upon the closure of the normal contact of relay 116, relays 117 and 121 operate over a circuit from battery through the winding of relay 117, left-hand contact of relay 120, winding of relay 121, right-hand normal contact of relay 118, right-hand alternate contact of relay 124, normal contact of relay 116 and the normal contact of supervisory relay 94 to ground. Relay 121 in operating completes a locking circuit for itself and relay 117 from battery through winding of relay 117, left-hand contact of relay 120, and the winding and right-hand alternate contact of relay 121 to ground. Relay 121 by opening its left-hand normal contact causes the deenergization of slow releasing relays 123 and 124. Relay 121 by closing its left-hand alternate contact grounds the signal control lead C' which is connected to the second of the two contacts, on the level a' of the automatic selector switch G', allotted to trunk line L'. The energization of relay 117 causes the energization of the start magnet 30' whereupon the motor magnet MM' advances the selector switch until the brush a' engages the contact to which the signal control conductor C' is connected. Relay 32' thereupon operates and locks up in the manner hereinbefore described, stopping the motor magnet MM'. Relay 120 then operates over a circuit from battery through the contacts of relays 34' and 33', right-hand alternate con-

the second of the two terminals on level *a* of the selector switch *G* allotted to trunk line *L*¹. Motor magnet *MM* functions upon the energization of the start magnet *30* to advance all brushes of the selector switch *G* until the brush *a* engages the contact to which signal control conductor *C*¹ is connected, whereupon the relay *32* operates and locks up, opening the circuit of the motor magnet. The operation of relay *32* completes a circuit through the right-hand winding of relay *76* which may be traced from battery through the contacts of relays *34* and *33*, upper alternate contact of relay *32*, brush *b*, restoring conductor *D*¹ and the inner right-hand alternate contact and right-hand winding of relay *76* to ground. This relay *76* thereupon becomes differentialized and releases its armatures. Brushes *1*, *2*, *4* and *5* of the selector switch *G* now connect positive current with individual sending segments *1*, *2*, *4* and *5* of the sending distributor *S*, while brushes *3* and *6* connect negative current with the individual sending segments *3* and *6*. The closure of the lower alternate contact of relay *32* energizes the release magnet *SRM* of the sending distributor to release the brush *9*, which, in making a complete revolution, transmits over the common conductor *P* a combination of impulses corresponding to the polarities connected with the individual sending segments of the distributor. The transmitted impulses are received at the office *Y* by means of the relay *25'* and the receiving distributor *R'*, causing the energization of relays *43'* and *46'* and the locking up thereof through the respective upper windings and upper alternate contacts thereof, and the contact of the deenergized relay *82'*. Relays *51'* and *52'* operate upon the energization of relay *48'* so that when the brush *10'* engages segments *20'* and *21'*, signal receiving relay *85* is differentialized, due to a positive impulse from the positive battery *99'* through the lower alternate contact of relay *46'*, segment *20'*, brush *10'*, segment *21'*, lower normal contacts of relays *45'* and *50'*, lower alternate contact of relay *51'*, upper normal contacts of relays *53'* and *58'*, signal receiving conductor *E*¹ and the left-hand winding of signal receiving relay *85* to ground. Relay *85* thereupon releases its armatures. The opening of the right-hand alternate contact of relay *85* causes the release of relays *123* and *124*, and the closure of the normal contact of relay *85* causes the lighting of the lamp *90* over a circuit from battery through the right-hand normal contact of relay *85*, lower alternate contact of relay *91* and the lamp *90* to ground. The lighting of the lamp *90* now serves as a disconnect signal to the operator at the office *Y*. The opening of the left-hand alternate contact of relay *85* opens the circuit which

includes supervisory relay *94* and relay *106*, whereupon both of these relays release their armatures. The opening of the alternate contact of supervisory relay *94* restores relays *116* and *119* to normal condition. Relay *146* is energized after the release of relay *94* and before the release of relay *116*, but is deenergized upon the opening of the alternate contact of relay *116*. The energization of relay *146* does not at this time perform any useful function. The release of relay *106* of toll switching trunk circuit *M* causes the lighting of lamp *104* over a circuit from battery through the lamp *104*, lower alternate contact of relay *102*, resistance *105* and normal contact of relay *106* to ground. The lighting of the lamp *104* now serves as a disconnect signal to the toll switching operator at the office *Z*. The operators at the office *Y* and the office *Z*, upon observing the lighted condition of the respective supervisory lamps *90* and *104*, may withdraw the plugs *110* and *100* from the respective jacks *111* and *101*, thereby restoring all apparatus to normal condition.

Subscriber on telephone line N, recalls operator at office X.

Should the subscriber at the station on telephone line *N* after answering a call, when connection is established between the toll cord circuit *F* and the telephone line *N* by way of the trunk line *L*¹ and the toll switching trunk circuit *M*, wish to signal the operator at office *X*, this may be done by repeatedly opening and closing the switchhook contact at the station on line *N*. It will be remembered that while the receiver at station on line *N* is off the switchhook and the switchhook contact is closed, supervisory relay *94* and all relays *116*, *117*, *118*, *119*, *120*, *121*, *122*, *123* and *146* controlled by the supervisory relay are deenergized. Of the other relays associated with the incoming end of the trunk line *L*¹, signal receiving relay *85* and relays *91* and *112* are energized, while signal receiving relay *93*, ringing relay *114* and the slow-releasing relays *92*, *135* and *136* are deenergized. Relay *116* is made slow in releasing so that its alternate contact will be held closed and its normal contact open during the short periods when the alternate contact of supervisory relay *94* is open while the subscriber of telephone line *N* is repeatedly opening and closing the switchhook contact to signal the operator at office *X*. Similarly relay *146* is made slow in releasing so that it holds up during the short periods when the normal contact of the supervisory relay *94* is open. Relays *122*, *123* and *124* are also made slow in releasing to assist in the control of the recall signal before the operator at the office *X* when the subscriber of telephone line *N* is recalling this operator.

Upon the first opening of the switchhook

contact at the station, over telephone line N, supervisory relay 94 is energized, whereupon relays 116, 117, 118 and 123 operate in the manner previously described. Upon 5 the operation of relay 117, the automatic selector switch G' advances until the brush a' engages the contact to which signal control conductor A' is, temporarily grounded, connected, when relay 32' operates. Relay 120 then operates to deenergize relays 117 and 118, the deenergization of the latter causing the energization and locking up of relay 124. The operation of relay 32' causes the energization of the release magnet 10 S'RM, whereupon the sending distributor S' transmits over the common conductor P a combination of impulses determined by the polarities connected with the individual sending segments 1' to 6', by the brushes 15 1' to 6', respectively. The receiving distributor R, at the office X, functions upon the reception of the transmitted combination of impulses by the relay 25 to cause the temporary deenergization of relay 82 and 20 temporary energization of relays 43, 51 and 52, whereby signal receiving relay 77 is energized and locked up. Marginal relay 72 then operates to light the supervisory lamp 131. Relay 75 is deenergized upon the operation of relay 77. The closure of the switchhook contact shortly after the opening thereof causes the deenergization of the supervisory relay 94. Relay 119 is immediately 25 deenergized and relay 122 energized. Then, upon the energization of the supervisory relay 94, in response to the next opening of the switchhook contact, relays 117, 118 and 119 operate as before described. Upon the 30 operation of relay 118, relay 122 is energized over a circuit from battery through the right-hand alternate contact of signal receiving relay 85, winding and right-hand normal contacts of relay 122, left-hand alternate contact of relay 124, and the right-hand alternate contact of relay 118 to ground. Relay 122 immediately locks up 35 through its right-hand alternate contact and the left-hand normal contact of relay 121 to ground. Upon the energization of relay 122, relay 119 is locked up over a circuit from battery, through the winding of relay 119, alternate contact thereof, middle alternate contact of relay 122, and the left-hand normal contact of relay 121 to ground, 40 whereby relay 119 is removed from the control of the supervisory relay 94, during the rapid energization and deenergization thereof, while the switchhook contact is being rapidly opened and closed to signal the operator at the office X. The energization of relays 117 and 118 causes the automatic selector switch G' to start the sending distributor S' which transmits over the conductor the combination of impulses corre-

sponding to trunk line L¹, and determined by the brush a', connecting with the temporarily grounded signal control conductor A'.

Upon the reception of these impulses by the relay 25 at office X, the receiving distributor R functions again to cause the temporary deenergization of relay 82 and the temporary energization of relays 43, 51 and 52 as before. When the brush 10 engages segments 20 and 21, signal receiving relay 98 operates over a circuit from the negative battery 86 through the normal contact of relay 46, segment 20, brush 10, segment 21, lower normal contacts of relays 45 and 50, lower alternate contact of relay 51, upper 55 normal contacts of relays 53 and 58, signal receiving conductor E', contact of relay 75 and the left-hand winding of relay 98 to ground. Relay 98, in operating, completes a locking circuit for itself from battery 60 through the contact of relay 73 and the right-hand winding and right-hand alternate contact of relay 98 to ground. The operation of relay 98 connects an interrupter 97 in circuit with resistance 130, thereby substituting an interrupted ground for the continuous ground, which causes the intermittent operation of the marginal relay 72. The intermittent operation of relay 72 causes the intermittent lighting of the supervisory lamp 131 which serves as a recall signal to the operator at the office X, while the switchhook contact may be rapidly opened and closed many times but after the second opening the only effect produced upon the apparatus associated with the trunk line L¹ is the energization and deenergization of the supervisory relay 94 and no apparatus associated with the common signaling conductor P is affected thereby. Therefore when the called subscriber recalls, only two combinations of impulses, or two signals are transmitted over the conductor to cause the intermittent lighting of the supervisory lamp at the office X. 65 This intermittent lighting is at a constant rate, while the rate at which switchhook contact is opened and closed may vary. The intermittent lighting of the supervisory lamp which continues only so long as the rapid opening and closing of the switchhook contact continues, is a signal to the operator at the office X that the called subscriber is signaling.

If, after repeatedly opening and closing the switchhook contact to signal the operator at the office X, the subscriber at the station on telephone line N should leave the switchhook contact closed, then supervisory relay 94 is deenergized. After the comparatively 70 extended deenergization of this supervisory relay 94, relay 116 releases its armatures and upon the closure of its normal contact relays

117 and 121 operate over a circuit from battery through the winding of relay 117, left-hand contact of relay 120, winding of relay 121, right-hand normal contact of relay 118, right-hand alternate contact of relay 124, normal contact of relay 116 and the normal contact of supervisory relay 94 to ground. The energization of the relay 121 releases relays 119, 122, 123 and 124. The 5 operation of relay 121 also grounds the signal control conductor C^1 , and the operation of relay 117 causes the energization of start magnet 30'. The selector switch G' thereupon functions and the brushes thereof are 10 advanced step-by-step until brush a' engages the contact to which the grounded signal control conductor C^1 is connected. Then the control apparatus associated with the selector G' and sending distributor S' 15 function to cause the sending distributor S' to transmit the same combination of impulses transmitted at the time the receiver was removed from the switchhook when the subscriber responded to the operation of the 20 call bell. The reception of the transmitted impulses at the office X causes the transmission of a positive impulse from the positive battery 99 over the signal receiving conductor E^1 for differentializing signal re- 25 ceiving relays 77 and 98 whereby these two relays release their armatures disconnecting the interrupter 97 from circuit relation with the marginal relay 72. The relay 72 thereupon opens its contact and extinguishes the 30 supervisory lamp 131. Relay 75 operates upon the deenergization of relay 77. If, after repeatedly opening and closing the switchhook contact to signal the operator at the office X , the subscriber at the station 35 40 on line N should leave the switchhook contact open, as when the receiver is restored to the switchhook, supervisory relay 94 would be energized. An extended energization of the supervisory relay 94 causes the deenergization of the relay 146 which upon the closure of its normal contact causes the energization of relays 117 and 121 over a circuit from battery through the winding of relay 117, left-hand contact of relay 120, winding of 45 50 relay 121, right-hand normal contact of relay 118, right-hand alternate contact of relay 124, left-hand alternate contact of relay 122 and the contact of relay 146 to ground. The selector switch G' and the sending and receiving distributors S' and R thereupon function in the manner previously described 55 60 for causing the differentialization and release of the signal receiving relays 77 and 98, which in releasing disconnect the interrupter 97 from circuit relation with marginal relay 72. Following the release of the relay 121, brought about in the manner before described, upon the energization of relay 120, relays 117 and 118 are operated over

a circuit from battery through the winding 65 of relay 117, left-hand contact of relay 120, winding and left-hand normal contact of relay 118, left-hand normal contact of relay 119, right-hand contact of relay 120, right-hand normal contact of relay 121 and the alternate contact of supervisory relay 94 to ground. Relays 117 and 118 are locked up immediately upon the energization of relay 118 and relay 119 operates shortly after the 70 75 energization of relay 118 to open the original energizing circuit of relay 118. The energization of relays 117 and 118 results in the operation of the selector switch G' and the sending and receiving distributor S' and R for sending and receiving a combination 80 of impulses corresponding to the polarities connected with the individual sending segments 1' to 6' by means of the brushes 1' to 6', the polarities being those connected with the first contacts of the first six levels on 85 switch G' allotted to trunk line L^1 . Upon the reception of these impulses by the relay 25 90 the receiving distributor R functions to cause the energization and locking up of signal receiving relay 77 whereupon marginal relay 72 operates to light the supervisory lamp 131 which now serves as a disconnect signal to the operator at the office X .

Operator at office X disconnects one cord circuit from and connects another cord circuit with trunk line L^1 .

If after the connection has been established between the cord circuit and the telephone line, by way of the trunk line L^1 , and 100 the toll switching trunk circuit M , should it be found that the connected cord circuit is noisy, the subscriber on line N may signal the operator at office X , by causing the intermittent operation of the supervisory 105 lamp 131 in the manner hereinbefore described. The operator at office X , after observing the intermittent lighting of the supervisory lamp, may connect the usual operator's telephone set (not shown) with 110 the engaged cord circuit and converse with the subscriber on telephone line N . Upon being advised that the engaged cord circuit is noisy, the operator at the office X may withdraw the plug 70 of the cord circuit F 115 from the jack 71 of the trunk line L^1 , and insert the plug of another cord circuit into the jack 71 of the trunk line L^1 , whereby a cord circuit, which is not noisy, is substituted for one which is noisy.

Upon the withdrawal of the plug from the jack 71, relay 78 is deenergized in precisely the same manner as when the ringing key is actuated, so that, if provision was not made to prevent it, ringing current 125 would be applied to the line of subscriber N when the second plug is inserted into the jack 71. In order to prevent this false ap-

plication of ringing current to the distant connected called line, the energizing circuit of the relay 74 includes the normally closed contact of relay 76, while the energizing circuit of relay 76 includes an alternate contact of relay 74 and is locked up immediately upon energization, so that when the plug is withdrawn from the jack 71, relay 74 is deenergized and cannot be energized again until after the deenergization of relay 76.

The sequence of operations resulting from the withdrawal of the plug from the jack 71 and the insertion of another plug therein, will now be described. Upon the withdrawal of the plug from the jack 71, relays 73, 74, 75 and 78 are released. Upon the release of relay 74, the start magnet 30 is energized, whereupon motor magnet MM advances the brushes of the automatic selector switch G until brush *a* engages the contact to which the grounded signal control conductor C¹ is connected. Relay 32 thereupon operates, following which relay 76 is differentialized and releases its armatures. As a result of the operation of the relay 32, the sending distributor S transmits a combination of impulses or code signal which, upon being received by the differential polarized relay 25' at the office Y, causes the functioning of the receiving distributor R'. Relay 82' is thereupon temporarily deenergized and relays 43', 46', 51' and 52' temporarily energized, so that when the brush 10' engages the segments 20' and 21', a positive impulse from the positive battery 99' is transmitted over the circuit including the right-hand winding of signal receiving relay 85. Relay 85 is thereby differentialized and releases its armatures, closing the circuit of and lighting the supervisory lamp 90. Immediately after the withdrawal of one plug from the jack 71, another plug is inserted therein, so that relays 73 and 75 are immediately energized. Relay 74, however, does not operate unless relay 76 has been previously deenergized in the manner before described or until relay 76 is deenergized. The energization of relay 74 causes the energization and locking up of relay 76, while relay 74, upon being energized, locks up through one of its alternate contacts. Upon the energization of relay 74 magnet 30 operates to close the circuits of the motor magnet MM which thereupon advances the brushes of the automatic selector switch G until the brush *a* engages the contact to which the signal control conductor A¹ is connected. Relay 32 then operates in the manner before described causing relay 78 to operate and lock up. The sending distributor S transmits over the signal conductor P a combination of impulses which, through the operation of the receiv-

ing distributor R', causes the transmission of the negative impulse from battery 86' over a circuit including the left-hand winding of signal receiving relay 85. Relay 85 thereupon energizes and locks up, opening the circuit of supervisory lamp 90, whereupon all apparatus is restored to the condition existing prior to the removal of the plug from the jack 71. The described operations follow each other so closely that the lamp 90 is lighted for a very brief interval.

The operations described above with reference to building up a connection over the trunk line L' with the telephone line N and the breaking down of such a connection are characteristic of those taking place in building up and breaking down a connection over any one of the trunk lines to which the signaling path P is common. The only essential difference in operation, so far as the establishment of connections over the different trunk lines is concerned, is that different code signals are employed for the different trunk lines, and while this invention is not limited to any particular arrangement of code signals the codes shown in the following table have been found to be very satisfactory for a total of thirty lines served by the same common signaling path.

Signals from office X to office Y.				Signals from office Y to office X.			95

In this table, the numbers in the first column indicate the numbers assigned to the trunk lines, while the numbers in the remaining columns indicate the order of the impulses of each group of six. The number "3" appearing in the first line in the second, third, fifth and seventh columns of the table means that the third impulse to be transmitted is negative, while the numbers "36"

in the fourth and sixth columns means that the third and sixth impulses to be transmitted are negative. The various code signals represented in the table are determined 5 by the polarities connected with the contacts of the first to sixth levels of the automatic selector switches G and G'.

What is claimed is:

1. In a telephone system, in combination, 10 a plurality of trunk lines and a signaling path common thereto extending between two stations, a signaling device at one station, means at the other station responsive to rapid changes in the condition of one of the 15 trunk lines to transmit only two successive signals over the signaling path, a signal receiving circuit at the one station and means controlled over the signal receiving circuit and responsive to the two transmitted signals 20 for causing the intermittent operation of the signaling device.

2. In a telephone system, in combination, 25 a plurality of trunk lines and a signaling path common thereto extending between two stations, a signaling device at one station, means at the other station responsive to rapid changes in the condition of one of the 30 trunk lines to transmit two successive signals over the signaling path, a signal receiving circuit at the one station, a signal receiving relay controlled over the signal receiving circuit and responsive to the first transmitted signal, a second signal receiving relay 35 conditioned for operation by the operation of the first signal receiving relay and responsive to the second transmitted signal to cause the intermittent operation of the signaling device, and means for maintaining the second signal receiving relay operated until the 40 deenergization of the first signal receiving relay.

3. In a telephone system, in combination, 45 a plurality of trunk lines and a signaling path common thereto extending between two stations, a signaling device at one station, means at the other station responsive to rapid changes in the condition of one of the 50 trunk lines occurring in rapid succession to transmit only two successive signals over the 55 signaling path, a signal receiving circuit at the one station, a signal receiving relay responsive to the first transmitted signal, and a second signal receiving relay connected with the signal receiving circuit upon the 60 operation of the first relay and responsive to the second transmitted signal to cause the intermittent operation of the signaling device.

4. In a telephone system, in combination, 65 a plurality of trunk lines and a signaling path common thereto extending between two stations, a signaling device at the station, means at the other station responsive to rapid changes in the condition of one of the

trunk lines to transmit two successive signals over the signaling path, a signal receiving circuit at the one station, a signal receiving relay controlled over the signal receiving circuit and responsive to the first transmitted signal, a second signal receiving relay 70 conditioned for operation by the operation of the signal receiving relay and responsive to the second transmitted signal, interrupter mechanism, and a circuit for the signaling device and the interrupter mechanism completed through contacts of the energized 75 signal receiving relays.

5. In a telephone system, in combination, 80 a plurality of trunk lines and a signaling path common thereto extending between two stations, a signaling device at one station, means at the other station responsive to changes in the condition of one of the trunk lines occurring in rapid succession to transmit two successive signals over the signaling path, a signal receiving circuit at the one station, a signal receiving relay controlled over the signal receiving circuit and responsive to the first transmitted signal, interrupter mechanism, and a second signal receiving relay 85 responsive to the second transmitted signal and co-operating with the first-named signal receiving relay for operatively associating the interrupter mechanism with the signaling device, thereby causing the intermittent operation thereof.

6. In a telephone system, in combination, 90 a plurality of trunk lines and a signaling path common thereto extending between two stations, a signaling device at one station, 100 means at the other station responsive to changes in the condition of one of the trunk lines occurring in rapid succession to transmit two successive signals over the signaling path and responsive to the cessation of such 105 changes to transmit another signal over the signaling path, a signal receiving relay at the one station energized in response to first transmitted signal and deenergized in response to the third transmitted signal, a second signal receiving relay at the one station energized in response to the second transmitted signal and deenergized in response to the third transmitted signal, and a signaling device operated by the cooperation of the 110 two signal receiving relays when energized.

7. In a telephone system, in combination, 115 a plurality of trunk lines and a signaling path common thereto extending between two stations, a signaling device at one station, a signal transmitter at the other station, means normally responsive to each change in the condition of one of the trunk lines for causing the transmitter to transmit a signal over the signaling path for controlling the signaling device, and means rendered effective by a plurality of such changes occurring 120 within a predetermined period for rendering

the normally responsive means non-responsive to all such subsequent changes following each other within the predetermined period.

8. In a telephone system, in combination, 5 a plurality of trunk lines and a signaling path common thereto extending between two stations, a signaling device at one station, a signal transmitter at the other station, means normally responsive to each change in condition of one of the trunk lines for causing the transmitter to transmit a signal over the signaling path, means responsive to signals transmitted within a predetermined period for causing the operation of the signaling 10 device, and means rendered effective by certain signals transmitted within said predetermined period for preventing the transmission of further signals in response to subsequent changes occurring within the predetermined period.

9. In a telephone system, in combination, 25 a plurality of trunk lines and a signaling path common thereto extending between two stations, a signaling device at one station, a signal sending device at the other station, a plurality of relays normally responsive to each change in condition of one of the trunk lines and coöperating to cause the signal sending device to transmit a signal over the 30 signaling path, means responsive to two signals transmitted within a predetermined period for causing the operation of the signaling device, and means rendered effective by the two operations of said relays within the predetermined period for preventing the transmission of further signals in response to subsequent changes within a predetermined period.

10. In a telephone system, in combination, 40 a plurality of trunk lines and a signaling path common thereto extending between two stations, a signaling device at one station and a signal sending device at the other station, a plurality of relays normally responsive to each change in condition of one of the trunk lines to cause the signal sending device to transmit a signal over the signaling path, means responsive to two signals transmitted within a predetermined period for causing the operation of the signaling device, and a relay energized in response to the two changes occurring within the predetermined period for preventing the further response of the signal sending device control relays 50 to subsequent changes occurring within a predetermined period.

11. In a telephone system, in combination, 60 a plurality of trunk lines and a signaling path common thereto extending between two stations, a signaling device at one station, means at the other station responsive to rapid changes in the condition of one of the trunk lines to transmit two successive signals over the signaling path, a signal receiving relay

responsive to the first transmitted signal, a 65 locking circuit for the signal receiving relay, and a second signal receiving relay responsive to the second transmitted signal and co-operating with the first signal receiving relay to cause the intermittent operation of the 70 signaling device.

12. In a telephone system, in combination, 75 a transmission circuit and a signaling path extending between two stations, a signaling device at one station, means at the other station responsive to rapid changes in the condition of the transmission circuit to transmit two successive signals over the signaling path, signal receiving relays responsive to the respective transmitted signals coöperating to cause the intermittent operation of the signaling device, and locking circuits for both signal receiving relays established upon the response of the respective relays for maintaining the intermittent operation of the signaling 80 device until another signal is received over the signaling path.

13. In a telephone system, in combination, 90 a plurality of trunk lines and a signal path common thereto extending between two stations, a signaling device at one station, means at the other station responsive to changes in the condition of one of the trunk lines following each other in rapid succession to transmit two successive impulses over the 95 signaling path, and signal receiving relays energized in response to the respective transmitted signals and coöperating for causing the intermittent operation of the signaling device and deenergized in response to a signal subsequently transmitted over the signaling 100 path.

14. In a telephone system, in combination, 105 a transmission circuit extending between two stations, a signaling path extending between the stations, a signaling device at one station, a signal transmitter at the other station, means normally responsive to each change in condition of the transmission circuit for causing the signal transmitter to transmit a 110 signal over the signaling path for controlling the signaling device, and means rendered effective by two such changes occurring within a predetermined period for rendering the normally responsive means 115 non-responsive to all subsequent changes following each other within the predetermined period.

15. In a telephone system, in combination, 120 a transmission circuit and a signaling path extending between two stations, a signaling device at one station, a signal transmitter at the other station, means normally responsive to each change in condition of the transmission circuit for causing the signal transmitter to transmit a signal over the 125 signaling path, means responsive to two signals transmitted within a predetermined

period for causing the operation of the signaling device, and means rendered effective by the two changes for preventing the transmission of further signals in response to subsequent changes following each other within the predetermined period.

16. In a telephone system, in combination, a transmission circuit and a signaling path extending between two stations, a signaling device at one station, means at the other station responsive to a plurality of successive rapid changes in the condition of the transmission circuit to transmit a less number of successive signals over the signaling path, and means at the one station responsive to the transmitted signals for causing the operation of the signaling device.

17. In a telephone system, in combination, a transmission circuit and a signaling path extending between two stations, a signaling device at one station, means at the other station responsive to a plurality of successive rapid changes in the condition of the trans-

mission circuit to transmit a less number of signals over the signaling path, and means 25 at the first named station responsive to the transmitted signals for causing the intermittent operation of the signaling device.

18. In a telephone system, in combination, a transmission circuit and a signaling path 30 extending between two stations, a signaling device at one station, means at the other station responsive to a plurality of successive rapid changes in the condition of the transmission circuit to transmit a less number 35 of successive signals over the signaling path and means at the first named station responsive to the transmitted signals for causing the intermittent operation of the signaling device.

In witness whereof, we hereunto subscribe our names this 4th day of August A. D., 1919.

WILLIAM L. DODGE.
HUGH D. MACPHERSON.
